DESCRIPTION

U.S. PATENT DOCUMENTS

D176,316 S 12/1955 Fleming
D207,919 S 6/1967 Fai
5,054,903 A 10/1991 Jannard et al.
D322,975 S 1/1992 Bolle

FIG. 1 is a front perspective view of a set of eyeglass components showing an embodiment of our new design;
FIG. 2 is a front elevational view thereof;
FIG. 3 is a rear elevational view thereof;
FIG. 4 is a left side elevational view thereof, the right side elevational view being a mirror image thereof;
FIG. 5 is a top plan view thereof; and,
FIG. 6 is a bottom plan view thereof.

The broken lines in the Figures show portions of the eyeglass which form no part of the claimed design.
